DESIGN FOR AN AIRSHIP

Sam T. Rogers, Washington, D. C.

Application July 14, 1938, Serial No. 78,490

Term of patent 14 years

To all whom it may concern:

Be it known that I, Sam T. Rogers, a citizen of the United States, residing at Washington, in the District of Columbia, have invented a new, original, and ornamental Design for an Airship, of which the following is a specification, reference being had to the accompanying drawings, forming part thereof.

Fig. 1 is a top plan view of an airship, showing my new design.

Fig. 2 is a bottom plan view.

Fig. 3 is a side elevational view.

Fig. 4 is a front elevational view.

Fig. 5 is a rear elevational view.

I claim:

The ornamental design for an airship, as shown.

SAM T. ROGERS.
